UNITED STATES PATENT OFFICE.

CLAUDE L. POST, OF CHICAGO, ILLINOIS.

ADJUSTABLE INKING MECHANISM.

Application filed September 8, 1921. Serial No. 499,157.

To all whom it may concern:

Be it known that I, CLAUDE L. Post, a citizen of the United States, residing at Chicago, in the county of Cook and State 5 of Illinois, have invented certain new and useful Improvements in Adjustable Inking Mechanisms, of which the following is a description.

My invention relates to inking mechanisms, and more particularly to an inking roll having an ink receiving reservoir therein which may be conveniently filled, and being provided with adjustable means whereby the ink in said reservoir may be fed in any desired amounts to the inking surface of the inking roll intermittently.

Another object of my invention is to provide means for reciprocating the inking roll while it is being rotated so that the ink 20 is more evenly distributed on the cooperating inking rolls or distributing rolls over their entire surfaces.

Another object of my invention is to provide a device of the character described 25 which may be easily assembled or disassembled for inspection or the like, and which is extremely simple, durable, compact, efficient and satisfactory for use wherever found applicable.

Many other objects and advantages of the construction herein shown and described 30 will be obvious to those skilled in the art from the disclosure herein given.

To this end my invention consists in the 35 novel construction, arrangement and combination of parts herein shown and described, and more particularly pointed out in the claims.

In the drawings, wherein like reference 40 characters indicate like or corresponding parts,

Fig. 1 is a top view of my improved inking roll held in position in the printing frame;

Fig. 2 is an enlarged sectional view taken 45 on the line 2-2 of Fig. 1;

Fig. 3 is an enlarged sectional view taken on the line 3-3 of Fig. 1;

Fig. 4 is a sectional view taken substantially on the line 4-4 of Fig. 2;

Fig. 5 is a sectional view taken substantially on the line 5-5 of Fig. 4;

Fig. 6 is a fragmentary plan view of the inking roll shown in Fig. 1;

Fig. 7 is an end elevation of a portion of the printing frame with my device in place;

Fig. 8 is a front elevation of the same with portions broken away;

Fig. 9 is a sectional view taken substantially on the line 9-9 of Fig. 7; 60

Fig. 10 is a sectional view taken substantially on the line 10-10 of Fig. 7;

Fig. 11 is a sectional view taken substantially on the line 11-11 of Fig. 10; and

Fig. 12 is a sectional view taken substantially on the line 12-12 of Fig. 8.

Referring to the drawings, where I have illustrated the preferred embodiment of my invention, 1 indicates the side frames of a printing mechanism of any suitable or desired construction, said frame having upwardly extending pairs of arms 2-2 at its opposite sides, and there being a slot 3 between each of said pair of arms. Rolls 4, 5, 6 and 7 are suitably held in place or carried by said frame, the rolls 4 and 5 being adjustably journaled therein in journal boxes 8, as shown in Figs. 1 and 2. The rolls 4 and 5 are suitably geared together or driven by any suitable means, not shown. 80

The shaft 9 of the roll 6 is annularly slotted at 10 so as to receive the yoked end 11-11 of a reciprocating arm 12, said arm being pivoted at its end and adapted to be oscillated on said pivot through suitable 85 gearing. The gearing for oscillating the arm 12 comprises a worm gear 14 at the end of the drive shaft 15 of the roll 5, said worm meshing with a gear wheel 16, carried by an arm 17 secured to the frame in any suitable manner. A pin 18 projects from the face of the gear wheel 16, and is adapted to slide in a longitudinal slot 19 provided in the arm 12, said pin 18 being eccentric to the pivotal axis of the gear wheel 16. It 90 is obvious that as the shaft 15 rotates, the worm 14 will rotate the gear wheel 16 and the eccentrically mounted pin 18 will slide in the slot 19 to oscillate the arm 12 on the pivot, this movement being transmitted to 95 the roll 6.

The inking roll 7 is in frictional contact with the roll 6, as shown in Figs. 1 and 2, the shaft 20 supporting said roll at its ends. A bearing sleeve 21 surrounds the shaft 20, 100 said bearing sleeve being cut away or recessed between its ends, as at 22, on opposite sides so as to non-rotatably fit between the opposed pair of frame arms 2, as shown in the drawings. In order to prevent longitudinal or axial movement of the sleeve relatively to the frame, a collar 23 is positioned 110

about the sleeve and adjustably secured thereto by a set screw 24, or any other suitable or equivalent means for the purpose, the collar 23 being recessed on opposite sides, 5 as at 25, and providing shoulders 26 overlying the opposite sides of the frame arms 2, thus preventing relative lateral movement therebetween, but permitting the sleeve, with its attached collar, to be slid into place 10 downwardly between the spaced arms 2, as shown in Fig. 1. The collar 23 is of a lesser length than the length between the shoulders or ends of the recesses 22 so that the sleeve may be adjusted relative thereto. 15 The inking roll 7 has an ink well or ink-receiving chamber 27 therein, said chamber being formed by slotting the roll longitudinally thereof, said slot opening on the periphery of the roll. Within the chamber 20 27 is revolvably mounted a roller 28, supported by a shaft 29 at its ends, the periphery of the roller being substantially flush with the peripheral surface of the roll 7, as shown in Fig. 9. At one end of the shaft 29 25 is mounted a gear or ratchet wheel 30, said gear being adapted to be intermittently engaged by a preferably resilient or yieldable tooth member 31 carried by the sleeve 21. As the roll 7 is in frictional contact with 30 the roll 6, it is driven and reciprocated thereby, and the teeth of the gear 30 which is eccentrically mounted relative to the rotational axis of the roll 7 will be intermittently engaged by the laterally offset or 35 projecting tooth end 32 of the resilient member 31 as shown in Figs. 2 and 6, whereupon the roller 28 will be partially rotated relative to the rotation of the roll 7 so as to carry the ink to the periphery of the roll 7, where it may be distributed to the roll 6 and to the type roll, as desired. 40

The ink reservoir may be closed by any suitable means, and removably held in place. In the embodiment shown, the cover 33, having downturned or laterally offset ends 34, 45 is pivotally mounted on the roll 7 by screws 35 through said ends, or any other equivalent means for the purpose, said cover being arcuate or curved in cross section to conform to the peripheral surface of the roll 7, and overlying one edge of the slotted chamber 27. The screws may be tightened to hold the cover firmly in place, or any other suitable or preferred latching means, such 50 as a spring-pressed detent, may be used.

Whenever it is desired to fill the chamber or to open it for inspection, or for any other desired purpose, the cover is drawn back, as 55 shown by the dotted lines in Fig. 9, whereupon easy access is had to the chamber 27 and to the parts therein.

It is well known that printing inks vary in their consistency or in "body", and therefore I have provided means for regulating the flow of the ink from the reservoir to the periphery of the printing roll to compensate for this variation in the body of the inks. The end walls of the roll 7 are bored and screw-threaded as at 36 (see Fig. 4), and into these threaded apertures are adjustably positioned bushings 37, said bushings having screw-threads 38 on their exterior, cooperating with the threads 36, and also being provided with a head 39 preferably of square, hexagonal or other suitable non-circular peripheral outline, so that it may be readily turned by hand or by any suitable tool. The bushings 37 are eccentrically bored at 40, to form bearings for the axle 29 of the roller 28. 65 70 75 80

Thus it will be seen that if the bushings 37 are partially rotated, the roller 28 will be adjusted radially of the printing roll to control the size of the opening leading to the periphery.

Having thus described my invention, it is 85 obvious that various immaterial modifications may be made in the same without departing from the spirit of my invention; hence I do not wish to be understood as limiting myself to the exact form, construction, arrangement and combination of parts herein shown and described, or uses mentioned. 90 95

What I claim as new and desire to secure by Letters Patent is:

1. An ink roll having an ink reservoir therein opening onto the periphery, a roller extending longitudinally in said opening to control the flow of ink therethrough, and bushings removably carried by said roll at 100 opposite ends and each having an eccentric bore therethrough to provide bearings for said roller, whereby said bushings may be independently adjusted to move said roller radially to regulate the passage of ink 105 through said peripheral opening.

2. An ink roll having an ink reservoir therein opening onto the periphery, a roller in said opening to control the flow of ink therethrough, and eccentrically bored bushings in said roll at opposite ends to form bearings for said roller, whereby said bushings may be adjusted to move said roller radially to regulate the passage of ink 110 through said peripheral opening. 115

In testimony whereof, I have hereunto signed my name in the presence of two subscribing witnesses.

CLAUDE L. POST.
